UNITED STATES PATENT OFFICE.

FREDERICK L. GOSS, OF CHICAGO, ILLINOIS, ASSIGNOR OF ONE-HALF TO
CHARLES J. STROMBERG, OF SAME PLACE.

PRINTER'S INK-FOUNTAIN KNIFE.

SPECIFICATION forming part of Letters Patent No. 247,903, dated October 4, 1881.

Application filed July 13, 1881. (No model.)

To all whom it may concern:

Be it known that I, FREDERICK L. GOSS, of the city of Chicago, Cook county, and State of Illinois, have invented a new and useful Printer's Ink-Fountain Knife, of which the following is a specification.

My invention relates to a knife to be used in taking the ink from the fountain of printing-presses; and the objects of my invention are to furnish a knife of such a shape and so constructed that it will expeditiously and thoroughly take the ink from the fountain, and also so shaped as to take the ink from under the fountain-cylinder.

The knives heretofore in use will not take the ink from under the cylinder, and will not thoroughly clean the fountain.

I attain my objects by the particular construction and shape of my device, as shown in the accompanying drawings, in which—

Figure 1 is a side view of my knife. Fig. 2 is a perspective view, showing the cylinder and fountain blade and the knife in use, and how it fits around the cylinder. Fig. 3 is a sectional view.

A represents my new knife.

B is the handle made in the shape shown in Fig. 1, or in any other suitable shape, and of wood or any other suitable material.

C is the blade of my knife, made of steel or any other material used for the blades of knives. It is made in the shape shown in Fig. 1, having a straight edge, d, on a direct line with the edge of the handle B, as shown in Fig. 1, being slightly curved at its connection with B, as designated by the letter e. b

is its end which is at right angles to the edge d, and of sufficient length to fit in the fountain and at its connection with the concave portion g forming a point.

g represents a small concave portion of the edge of the knife-blade uniting with the end b to make a point, and so concaved as to fit around the cylinder and make its point, which I designate by letter P, fit snugly under the cylinder.

h represents the balance of the edge of the knife-blade C, and extends from the part g to the handle B on an angle, as shown in Fig. 1, having a curved connection, k, at the handle similar to the curve e.

R is the cylinder of the fountain. K is the blade of the fountain.

The manner of operation is as follows: When it is desired to remove the ink from the fountain-blade K for any purpose or reason the knife A is inserted in the fountain, as shown in Fig. 2. The point P will fit snugly under the cylinder, and the ink be readily removed without any waste or loss of material, so common with the present appliances for renewal.

Having described my invention, what I claim, and desire to secure by Letters Patent, is—

In a printer's ink-fountain knife, the blade C, having straight edges d b, forming a right angle, inclined edge h, and concave g, substantially as shown and described.

FREDERICK L. GOSS.
